UNITED STATES PATENT OFFICE.

GEORGE A. HOLMES, OF NEWTON, MASSACHUSETTS.

SNAP-FASTENING BUCKLE.

No. 873,128.

Specification of Letters Patent.

Patented Dec. 10, 1907.

Application filed June 20, 1907. Serial No. 379,878.

To all whom it may concern:

Be it known that I, GEORGE A. HOLMES, a citizen of the United States, and resident of Newton, in the county of Middlesex and State of Massachusetts, have invented new and useful Improvements in Snap-Fastening Buckles, of which the following is a specification.

My invention relates to snap fastening buckles such as may be used to secure together the two ends of a girdle, garter or other garment, and has for its object the provision of a snap fastener buckle which shall hold the strap end adjustable but securely and is adapted, moreover, to use with materials of different thickness and texture.

In the drawings hereto annexed,—Figure 1 is a plan view of a snap fastener buckle containing my improvement; Fig. 2 is a cross section of the buckle plate shown in Fig. 1; Fig. 3 is a plan view of a modification; Fig. 4 is a cross section of Fig. 3 showing a strap attached; Fig. 5 is an elevation of a stud; and Fig. 6 is a plan view of a buckle with strap attached.

A particular object in the present improvement is to provide a buckle which shall have the advantage of a tongue buckle and at the same time possess the simplicity essential to a snap fastening buckle plate.

In the figures, A is a buckle plate with parallel slots on either side at b with a central perforation at d wherein a snap fastener member such as an eyelet e may be secured.

In Figs. 1, 2, 3 and 4 I show a short tongue c formed on a tongue piece C which is mounted upon the central eyelet e and is capable of a turning movement upon the plate A, which is sometimes of assistance in making the engagement between the tongue c and the perforation of the strap M.

As shown in Fig. 4, the strap M is threaded up through one of the slots b over the plate A

and down through the opposite slot b. The strap has holes provided at intervals in the usual manner and any one of these holes may engage with the tongue c and thus secure a strap in its desired adjustment.

In Fig. 1 the tongue piece C is provided at the side opposite the tongue c with a cross head c' which lies adjacent to one of the slots b so that the bearing of the strap M against the cross head c' holds the tongue c squarely presented and prevents its withdrawal from the perforations of the strip. Moreover, any tendency of the strap or buckle plate to twist is accompanied by a tendency of the tongue piece to turn and thus to cause one side or the other of the cross head c' to bind more tightly against the strap.

What I claim and desire to secure by Letters Patent is:

1. In a snap fastening buckle, the combination of a plate, a snap fastener member secured centrally thereon, the plate having a pair of slots, one on either side of the fastener member, a tongue piece loosely secured on the fastener member and having a buckle tongue projecting therefrom over one of the slots.

2. In a snap fastening buckle, the combination of a plate, a snap fastener member secured centrally thereon, the plate having a pair of slots, one on either side of the fastener member, a tongue piece loosely secured on the fastener member and having a buckle tongue projecting therefrom over one of the slots, and a cross head on the side opposite the tongue and adjacent to the opposite slot.

Signed by me at Boston, Massachusetts, this 31st day of May 1907.

GEORGE A. HOLMES.
